CLOTHES-PRESSING MACHINE, (DRYING ATTACHMENT.)

1,319,108.

Specification of Letters Patent.

Patented Oct. 21, 1919.

Application filed May 9, 1918. Serial No. 233,495.

To all whom it may concern:

Be it known that I, THEODORE D. PALMER, a citizen of the United States of America, and resident of Syracuse, in the county of 5 Onondaga, in the State of New York, have invented new and useful Improvements in Clothes - Pressing Machines, (Drying Attachments,) of which the following, taken in connection with the accompanying drawings, is a full, clear, and exact description.

This invention relates to certain improvements in garment pressing machines of the class set forth in my Patent No. 1,177,571, March 28, 1916, in so far as it contemplates 15 the use of air for drying purposes but is distinguished therefrom in the method of and means for applying the air to the garment and pads of the pressing elements.

These garments are brought to the machine in a dry and more or less dusty unsanitary condition to be cleaned, sterilized and restored as far as possible to their original shape and newness of appearance which is usually accomplished by the simultaneous 25 application of moisture, pressure and heat, after the garment has been previously brushed to remove the loose dust.

I have found, however, that pre-cleaning a garment by means of a brush as usual is 30 not only insufficient to remove the dust which becomes embedded in the interstices of the fabric but produces an excessive wear of the nap by reason of the rubbing contact so that when the garment is moistened by 35 steam or equivalent moistening means, the embedded dust becomes matted in the fabric, particularly during the pressing and drying operation, and the main object of my present invention is to produce a more efficient and expeditious removal of the dust, 40 not only from the surface but also from the interstices of the fabric by forcing or drawing a cleaning agent therethrough according to the nature of the fabric.

In other words I have sought to provide 45 the machine with simple and convenient means for passing a current of air or other cleaning agent through the fabric by pressure or suction or alternately by pressure 50 and suction so that the fabric will be entirely free from foreign matter prior to the moistening, pressing and drying operation thereby increasing the life of the fabric and

permitting it to be more effectively restored to its original condition and shape. 55

Another object is to utilize the same cleaning device for removing the vapor and moisture from the garment and the padded surface of the pressing elements upon which it is supported. 60

Other objects and uses relating to specific parts of the machine will be brought out in the following description:

In the drawings—

Figure —1— is a side elevation, partly in 65 sections, of a portion of a garment pressing machine and my improved cleaning and steam removing attachment operably connected thereto.

Figs. —2— and —3— are enlarged detail 70 sectional views of the valves for controlling the air currents used for cleaning and drying purposes.

Fig. —4— is a top plan of a portion of a garment presssing machine showing a modified form of cleaning and drying apparatus applied thereto.

Fig. —5— is a transverse vertical section 75 tional view taken on line 5—5 Fig. —4—.

Fig. —6— is an enlarged side elevation, 80 partly in section, of the machine shown in Figs. —4— and —5—, showing the connection of the cleaning device with the steam distributing chamber of the buck.

Fig. —7— is an enlarged longitudinal 85 vertical section taken in the plane of line 7—7 Fig. —6—.

The pressing machine shown in Fig. —1— comprises a stationary horizontal buck —1— and a vertically movable press head —2— 90 mounted upon a rock arm —3— which in turn is fulcrumed at —4— upon a main supporting frame to swing about an axis parallel with the longitudinal center of the buck and some distance to the rear thereof, 95 to enable the garment to be drawn over either side or end, the rear end of the rock arm —3— being provided with a weight similar to that shown in Figs. —4— and —5— for counter-balancing the press head —2—.

The buck —1— is supported in the manner shown in Fig. —5— in a horizontal position on the main supporting frame —5— and is provided with a heating chamber 105 —6— and steam distributing chamber —7—

having a perforated top —8— covered by a press cloth or pad —9—.

The heating chamber —6— is separated from the distributing chamber —7— by a 5 horizontal partition —10— which forms the top wall of the heating chamber and the bottom wall of the distributing chamber and serves not only to heat the steam admitted to the distributing chamber but also to heat 10 the superposed press plate —8— and pad thereon.

The steam chamber —7— is nearly coextensive in area with that of the buck and overlies the entire area of the heating chamber —6—, steam being supplied to both of 15 said chambers through branch pipes —11— and —12— of a main steam supply pipe —13— which may be connected to any suitable source of steam supply.

20 The branch pipe —11— is normally open for maintaining a constant supply of steam to the heating chamber —6— which however, is provided with a drain pipe —14— having a normally closed valve —15— capable of being operated at will to drain any 25 water of condensation from the chamber —6—.

The branch pipe —12— is provided with a normally closed valve —16— adapted to 30 be opened at will by an operating member —17— to supply a blast of steam to the garment through the distributing chamber —7—, perforated plate —8— and pad —9—.

The cleaning attachment as shown in Fig. 35 —1— comprises an air reservoir —18— in which air is maintained under pressure by means of a steam pump —19— through a supply pipe —20— which in turn is connected by a branch pipe —21— to an air 40 pressure regulator —22— for controlling the steam valve as —23— in a branch supply pipe —24— leading from the main supply —13— to the valve chest of the pump operating engine, the pressure regulator —22— 45 being operated by air pressure from the tank —18— or pump to close the valve —23— when the pressure reaches a certain degree 50 in the reservoir —18— and to open said valve when the pressure is below that degree, said pressure being indicated by a gage —25— on the top of the tank —18—.

A tubular head —26— is swiveled by means of a ball and socket or an equivalent universal joint —27— to the upper end of a 55 branch pipe —28— and is provided with an extensible pipe or section —29— telescoping therewith and equipped at one end with a fan shaped nozzle —30— adapted to be moved to and from a position between the pressing 60 elements —1— and —2— and across the upper face of buck —1— or garment resting thereon.

The ball and socket joint —27— is hollow, thus forming a continuation of the branch 65 pipe —28— and communicates with a port

—31— which extends along the tubular head or pipe —26— to a point a short distance from the rear end thereof.

The rear end of the pipe section —29— constitutes a valve or piston normally closing the port —31— when moved to its extreme rear position but adapted to open communication with said port when drawn forwardly so that its rear open end may communicate with the rear end of the port 75 —31—. The upper side of pipe —29— is provided with a lengthwise keyway —32— and an abutment —33— at the rear end thereof for engagement with a stop —34— on the front end of the pipe section —26— 80 to limit the forward movement of the nozzle —30— as shown by dotted lines in Fig. —1—.

The branch pipe —28— is connected to one side of a normally closed valve —35— which in turn is connected by a branch pipe —36— to an ejector —37— said valve being connected by an air supply pipe —38— to the reservoir —18—.

The distributing chamber —7— is connected to the suction side of the ejector by means of a pipe —39— having a normally closed valve —40— which in turn is connected by a pipe —41— to the branch —28— to form a by-pass between the said distributing chamber and reservoir around the ejector —37—.

The valve —40— is preferably of the three-way type adapted when adjusted in one position as shown by full lines in Fig. 100 —2— to open direct communication between the suction side of the ejector —37— and distributing chamber —7— and also between the same suction side and the port —31— of the head —26— and when in another position 105 to open communication between the distributing chamber —7— and branch pipe —28— through the by-pass pipe —41—, the valves —35— and —40— being controlled at will by suitable operating members —35'— and 110 —40'— respectively.

The object of connecting the reservoir —18— to the distributing chamber —7— and to the tubular head —26— in the manner just described is to create a rapidly moving air current in either chamber or pipe or both above atmospheric pressure so that the garment or pad may be cleaned by an air blast or by suction as controlled by the valves —35— and —40— and also by the longitudinal movement of the nozzle section —29—.

For example, if it is desired to clean or dry the garment or pad or to remove the steam therefrom by air blast through the nozzle —30— it is simply necessary to adjust 125 the valve —35— to one position indicated by dotted lines in Fig. —3— for establishing communication between the pipes —38— and —28— which cuts off communication between the pipe —38— and ejector —37—, 130

the valve —40— being closed as shown by its tilted dotted position in Fig. —2—.

Under these conditions the air pressure of the tank —18— will be exerted at the port

5 —31— and by drawing out the nozzle —30— by means of its handle —30'— toward the position indicated by dotted lines —31—, communication will be established between the port —31— and interior of the pipe section —29— thus allowing the blast of air to pass through the nozzle —30— which may be moved across or upon the pad —9— or garment thereon to remove the dust therefrom prior to applying the moisture or to 15 remove the vapor and dry the garment and pad, following the pressing operation.

If it is desired to project a blast of air through the pad —9— and garment thereon from the under side simultaneously with 20 the application of the blast of air from above through the nozzle —30—, it is simply necessary to adjust the valve —40— to the horizontal position shown by dotted lines in Fig. 2 so as to establish communication between 25 pipes —39— and —41— and cut off communication between the valve and suction side of the ejector so that a portion of the air from the reservoir —18— will pass through the pipes —41— and —39— and 30 thence into the distributing chamber —7— and through the padding —9— and garment thereon.

On the other hand if it is desired to clean 35 the garment by air suction from the ejector —37— the valve —35— will be adjusted to establish communication between the pipes —36— and —38— and to cut off direct communication between the valve —35— and pipe —28— and to readjust the valve —40— 40 to the position shown by full lines in Fig. —2— to establish communication between the suction side of the ejector —37— and distributing chamber —7— and also between the same suction side and port —31— 45 of the tubular head —26—.

This latter adjustment will allow the air under pressure to go through the ejector —37— into the drain pipe —14— which will produce the desired suction in the distributing chamber —7— through the pipe —39—, said suction being at its maximum degree in the distributing chamber when the valve —33— on the rear end of the pipe —29— is closed.

55 Now if it is desired to use the nozzle —30— for suction purposes, it may be drawn out to the dotted position and moved across the face of the garment or the pad upon which it rests to assist in withdrawing the dust therefrom prior to pressing or may be used for withdrawing the steam and drying the garment and pad, following the pressing operation.

After the operation either by air blast 60 or air suction in the manner just previously

described, the valves —33—, —35— and —40— may be restored to their normal positions and the pressing machine operated in the usual manner.

The pressing elements shown in Figs. 70 —4— to —6— inclusive are similar to those shown in Fig. —1—, the upper press head —2— being provided with a steam heated chamber —42— and a distributing chamber —43— having the usual perforated bottom 75 covered by a press cloth.

The cleaning and drying attachment used in connection with these pressing elements comprises a blower —44— and a suction device —45— having rotary members or fans 80 mounted coaxially upon the same rotary shaft —46— which is journaled in suitable bearings —47— on the main supporting frame —5— as shown more clearly in Fig. —7—, the bearings of said shaft also serving 85 to support the rock arm —3— for the head —2—.

The case of the blower —44— is adapted to rock with the head supporting arm —3— and is provided with a central inlet —48— 90 and a tangential outlet —49— connected by a pipe —50— to a delivery nozzle —51— extending along the front edge of the head —2—, and supported in fixed relation thereto by the pipe —50—, said nozzle being 95 provided with a lengthwise slot or opening —52— facing the adjacent edge of the lower face of the head for discharging a blast of air upon the upper surface of the buck or garment thereon, as the head is raised from 100 its pressing position.

The pipe —51— extends across the upper side of the head —2— and is provided with a valve —53— and a branch pipe —54— leading therefrom to the distributing chamber —43—.

The suction side of the fan —45— is connected by a pipe —55— to the distributing chamber —7— of the buck —1— while the pressure side of the same fan is connected 110 to the atmosphere through the pipe —56—.

The shaft —46— with the rotary members of the pressure and suction devices —44— and —45— thereon are driven by suitable connection with the rock arm —3— so that 115 when the head —2— is raised a blast of air will be projected upon and across the surface of the buck —1— and garment thereon, and at the same time the suction device —45— removes the dust and vapor from the 120 under side of the garment through the distributing chamber —7—.

The means for transmitting motion from rock arm —3— to the shaft —46— consists of a tooth segment —60— rigidly secured to the rear end of the rock arm —3— and meshing with a pinion —61— on a counter shaft —62— which in turn is journaled upon the frame —5— parallel with the shaft —46— and is provided with a rela- 125 130

tively large gear —63— with a pinion —64— on the shaft —46—.

The ratio of the gear connections between the rock arm —3— and fan shaft —48— is 5 such that the movement of the press head from one extreme position to the other will cause a multiplicity of revolutions of said rotary members at high speed so that the air blast and suction operating upon both 10 sides of the garment may be efficient and practically instantaneous at the beginning of the opening movement of the head.

What I claim is:

1. In combination with a garment supporting bed, a conduit for supplying a cleaning agent under pressure, a suction device, a nozzle movable across the surface of the bed and connected to said conduit and to the suction device, means operable at will 15 for controlling communication between said nozzle and conduit, and additional means operable at will for controlling communication between said nozzle and the suction device.

2. In a garment pressing machine, the combination with coöperating pressing elements, of a garment cleaning device including an air pipe having a nozzle movable across the face of one of said elements when 30 the latter are separated, means for creating a rapidly moving air current through said pipe and nozzle, and means for changing the direction of said current at will.

3. In a garment pressing machine, the combination with coöperating pressing elements, a tubular head swiveled beyond the margin of said elements and provided with an air passage, a pipe telescoping with said head and provided with a nozzle movable 40 across one of the pressing elements when the latter are separated, and means for creating a rapidly moving current of air through the pipe and head.

4. In a garment pressing machine, the combination with coöperating pressing elements, a tubular head swiveled beyond the margin of said elements and provided with an air passage, a pipe telescoping with said head and provided with a nozzle movable 50 across one of the pressing elements when the latter are separated, and means for creating a rapidly moving current of air through the pipe and head, said pipe having a valve for controlling the passage of air therethrough.

5. In combination with a garment supporting bed having a perforated top and an underlying chamber, a nozzle movable across the surface of the bed, a suction device having its suction side connected to said chamber and to the nozzle, and means operable at will 60 for controlling communication between said suction device and chamber, and

also between the suction device and nozzle whereby dust and other foreign matter may be drawn from both sides of the garment 65 while supported on the bed.

6. The combination with a pressing couple for shaping garments, of an air pipe, a tubular head swiveled to said pipe and communicating therewith, a pipe section telescoping 70 with the tubular head and provided with a nozzle movable across the surface of one of the pressing elements, said pipe section having means for controlling said communication, and means for creating an air current 75 in the air pipe and nozzle section.

7. In a clothes pressing machine, a buck having a steam heated chamber and a steam distributing chamber, the latter chamber having an outlet for applying steam to a 80 garment on the buck, means for controlling the entrance of steam to the distributing chamber, and means movable about an axis at the rear of the buck and to and from the surface thereof for supplying air under pressure 85 to said surface and to a garment thereon.

8. In a garment pressing machine, the combination with coöperative pressing elements, one of which is provided with a 90 steam distributing chamber having an outlet for applying steam to a garment, means for supplying steam to said chamber, an air pressure reservoir, an ejector having its pressure side communicating with the reservoir and its suction side communicating with the steam-distributing chamber, and means for opening and closing communication 95 between said ejector and chamber.

9. In a garment pressing machine, the combination with coöperative pressing elements, one of which is provided with a steam distributing chamber having an outlet for applying steam to a garment, means for supplying steam to said chamber, an air 100 pressure reservoir, an ejector having its pressure side communicating with the reservoir and its suction side communicating with the steam-distributing chamber, and means for opening and closing communication 110 between said ejector and chamber, a by-pass between the reservoir and chamber around the ejector, a valve for controlling the passage of air to the ejector and by-pass, and a separate valve controlling communication 115 between the ejector and chamber.

In witness whereof I have hereunto set my hand this twenty-sixth day of March, 1918.

THEODORE D. PALMER.
